UNITED STATES PATENT OFFICE.

EDWIN HORSBURGH EVANS, OF LAYTONSTONE, ENGLAND.

DOUBLE-JOINTED OR UNIVERSAL-JOINTED BOX-SPANNER.

1,300,148.

Specification of Letters Patent. Patented Apr. 8, 1919.

Application filed September 27, 1917. Serial No. 193,577.

To all whom it may concern:

Be it known that I, EDWIN HORSBURGH EVANS, a subject of the King of Great Britain and Ireland, residing at 17 Chelmsford road, Laytonstone, in the county of Essex, England, have invented certain new and useful Improvements in Double-Jointed or Universal-Jointed Box-Spanners; and I do hereby declare the following to be a full, clear, and exact description of the invention, such as will enable others skilled in the art to which it appertains to make and use the same.

This invention relates to improvements in connection with double jointed or universal jointed box spanners and has for its object the properly screwing up of nuts in connection with the gland plates of water tight bulk head plates as fitted in refrigerating ships for the brine service pipes, or for any other purpose of a similar character where nuts are inaccessible to ordinary spanners, as for instance it is found in practice that many nuts are fitted in close proximity to pipes, around the flanges of elbow pipes where the screwing up of the nuts has to be performed right under the bend of such pipes, also on bulk heads and other situations where ordinary spanners cannot be applied on account of the said nuts being out of arm's reach.

Another object of this invention is to provide a universal box spanner or wrench for operating nuts which are not in convenient accessibility, suitable guide means being provided to facilitate the use of the wrench, and the parts of the wrench or spanner being so connected that the greatest rigidity will be attained.

In the accompanying drawings, Figure 1 illustrates the spanner in elevation showing the curved extremities of the outer fork *a* cut away which enables the inner fork *b* to be operated so that the desired angle can be arrived at.

Fig. 2 is a plan showing that the large fork or joint edgewise is no greater in width than the outside diameter of box spanner.

Fig. 3 is an end view in section along the line 3—3 of Fig. 1, showing the two pins connecting the joints together.

Fig. 4 is a plan view of the block through which the intersecting pins pass for connecting the forks together.

Fig. 5 is an elevational view of the same. 55

Fig. 6 is the spanner guide showing the clip and screws for attachment to *a*².

Fig. 7 is a transverse sectional view of guide, the section being taken along the line 7—7 of Fig. 6. 60

Fig. 8 is a side elevational view of one of the adapting sockets, the box of same to be made in various sizes to fit different size nuts, while the barreled shank in each remains the same diameter to operate in the permanent box of the tool; and 65

Fig. 9 is a plan view of the same.

In the various figures the letter *a* represents the outer fork or joint. The smaller or inner fork *b* being connected to the outer fork or joint by means of block *c* and pins *d* and *e*. The outer fork comprises a shank *a*² equipped with a box spanner or socket *a*³ on one end particularly for the purpose of receiving adapters or auxiliary sockets *a*⁴. 75 The other end of the spanner is forked and has the inner faces of its terminals beveled. The outer end of the handle of said inner fork is square to which a T handle or spanner of any description may be applied for 80 operating the box spanner to the desired angle for screwing up the nuts. *f* indicates the jaws of a guide, which jaws are adapted to loosely embrace the shank *a*². The jaws and handle *f*² of the guide are secured together 85 by means of a nut and bolt connection *f*³.

The adapter *a*⁴, as shown in Fig. 8, comprises a polygonal socket which has a squared extension formed thereon both ends of which are beveled. A pin *a*⁶ is mounted 90 in the spanner box *a*³ and through an opening *a*⁷ in the extension *a*⁵. The opening *a*⁷ is relatively larger than the diameter of the pin *a*⁶ to permit oscillation of the latter, thereby allowing the spanner head to assume a diagonal position on the extension for contact with the upper beveled end of the latter at one side and with the lower beveled end on the opposite side. 95

It is obvious that those skilled in the art 100 may vary the details of construction and arrangements of parts without departing from the spirit of my invention, and therefore I do not wish to be limited to such features except as may be required by the claims. 105

I claim—

1. A device as set forth including a socket equipped with a shank the free terminal of

which is forked, a handle movably mounted between the legs of the fork, and a guide loosely embracing said shank.

2. A device as specified including a socket
5 the inner periphery of which is polygonal
in configuration, means for rotating said
socket, an auxiliary socket equipped with an
extension polygonal in cross section for en-
gagement in said polygonal socket, said ex-
10 tension having its terminals beveled to per-
mit torsional movement of the extension in

the socket, said extension provided with an
opening therethrough, and means arranged
through said polygonal socket and the open-
ing in the polygonal extension to hold the
latter in the socket.

In testimony whereof, I affix my signature
in presence of two witnesses.

EDWIN HORSBURGH EVANS.

Witnesses:

HENRY ROLAND CARRIER,
EDWARD OLIVER TWIGG.
